UNITED STATES PATENT OFFICE

ALBERT A. McGUIRE, OF ROCKFORD, ILLINOIS

FASTENER FOR WALL BOARD

Application filed July 24, 1926. Serial No. 124,574.

This invention relates to improvements in wall and ceiling constructions for buildings and is principally concerned with the provision of a novel fastener for use in the application of wall board.

In the application of beaver board and other types of wall board it is now a common expedient to put up headers between the studding of the walls and the joists of the ceilings.

10 These have to be nailed in piece by piece at a considerable cost in labor and material. According to the present invention, fastener strips, suitably of sheet metal or of wire rod construction, are employed, each arranged to 15 take the place of a number of header pieces and to be nailed or stapled onto the studding or joists wherever the headers would otherwise be placed, that is, at the base-board, chair rail, and plate rail, or picture molding, in 20 walls, and behind the trimming strips or beams in the ceilings. These strips serve the purpose of supporting or backing up the wall board when the same is applied and are provided with prongs, spurs or barbs to become 25 embedded in the wall board and thereby grip and retain the same against creeping.

Another object of the invention is to provide sheet metal header strips formed in such a manner as to afford the requisite strength 30 and rigidity while permitting application to the studding and joists in such a way as not to affect the workmanlike fastening of the wall board thereto.

The invention is illustrated in the accompanying drawings wherein—

Figure 1 is a more or less schematic showing of a building construction employing header strips in accordance with the invention;

40 Fig. 2 is an enlarged sectional detail taken on the line 2—2 of Fig. 1 showing one form of header strip and illustrating how the same is fixed to the studding and serves to back up the wall board and retain the same by means 45 of the spurs or barbs provided thereon;

Figs. 3 and 4 are similar views of modified forms; and

Figs. 5 and 6 are perspective of still other modified forms.

50 Throughout the views the same or corre-

sponding reference numerals are applied to corresponding parts.

In the application of wall board, such as that shown at 10, to the studding 11 of the walls and joists 12 of the ceiling, it has 55 heretofore been common practice to provide headers to give an even nailing surface for the edges of every panel. It was particularly necessary to provide headers at the top of the base board 13 and behind the chair rail 60 14 and picture molding 15. A similar provision had to be made in the application of the wall board over brick and cement walls where the headers had to be applied between the furring strips to give a proper foundation 65 for the wall board. The header pieces have to be cut to size and handled piece by piece. It is furthermore a tedious job to nail these pieces between the studding and joists.

The labor cost is, therefore, quite an item and the material cost is also appreciable. According to the present invention, the purpose of the header pieces is served by metallic header strips 16 which may be provided in any suitable length convenient to handle. These strips are fastened across the studding and joists wherever the wooden headers would otherwise be employed. In Fig. 1 they are shown behind the top of the base board 13 and back of the chair rails 14, picture moldings 15, and the wood trimming 17 in the wall construction, and behind the ends of the wall board panels of the ceiling where the trimming strips or beams are usually provided.

The panel strips shown at 18 conceal the 85 joints in the wall construction and form part of the usual ornamental panel arrangement.

The header strips 16 may obviously be provided in various forms. The principal requirements are that they be sufficiently stiff to properly support and back up the wall board when the same is applied and that they provide some means for gripping the wall board to aid in retaining the same against 90 creeping. In the form illustrated in Fig. 2, the strip 16 is formed of sheet metal with a central longitudinally extending rib 19 and flanges 20 on the opposite edges thereof. The rib 19, it will be noted, is of a double thick- 95

ness and embeds itself readily in the studding especially if one of the nails 21 for fastening the strip is passed through the strip at this point. Otherwise the studding may 5 be notched out with a saw or chisel. However, it is not believed that this preliminary step will be found necessary. The flanges 20 being turned in toward one another and presenting rounded edges to make the strip 10 easier to handle are arranged to flatten out, as indicated at 22, and to become slightly embedded in the studding. There is thus practically only the thickness of the sheet metal 15 of which the strip is formed projecting from the studding which in no way affects the workmanlike application of the wall board. The strip 16 has a plurality of spurs or barbs 23 struck therefrom preferably in staggered 20 relation which embed themselves in the wall board when the same is applied. When a trimming piece such as the chair rail 14 is nailed to the studding as by means of nails 24 which are passed preferably through the header strip 16, the wall board is obviously 25 retained quite securely against bulging or warping. By providing two rows of the spurs or barbs 23 the edges of abutting panels lapped by the strip are properly gripped and retained.

30 In Fig. 3 a modified form of strip is illustrated at 16' having a corrugated cross section for the purpose of affording the necessary stiffness or rigidity to properly support and back up the wall board. As shown at 25, 35 this form of strip readily flattens out onto the studding when the nails 21 for fastening the same are driven home. Between the studding the strip retains its original corrugated form as illustrated. This form of strip is 40 also preferably provided with spurs or barbs 23 to become embedded in the wall board to grip and retain the same.

In Fig. 4 still another form of strip 16'' is shown which is flat in cross section with the 45 exception of two longitudinally extending ribs or corrugations 26. The latter give the required stiffness and rigidity and are arranged to become flattened out more or less, as indicated at 27, when the strip is fastened 50 to the studding as by means of the nails 21. The normal ribbed cross section is retained between the studding. In this form, as in the others, the spurs or barbs 23 are provided 55 preferably in two rows to become embedded in the edges of abutting wall board panels to grip and retain the same.

It is also contemplated, as stated above, to provide header strips of wire rod construction, as shown in Figs. 5 and 6. In the form 60 shown at 16^a a plurality of barbs 23 are provided at regularly spaced intervals to become embedded in the wall board for the same purpose as the barbs on the other forms of strips illustrated. The strip 16^a is obviously adapted 65 to be fastened to the studding by staples

and in fastening will easily become embedded in the studding to a sufficient depth so that the wall board will lie practically flush over the same. The strip 16^b is similar to the strip 16^a with the exception that two sets of barbs are provided in planes substantially at right angles. That is, alternate barbs occur in one plane while intermediate barbs occur in the other plane. Thus, if the rod becomes twisted so that one set of barbs does not project properly to become embedded in the wall board, the other set of barbs will be properly disposed and no special precaution has to be taken in the fastening of the strip as might have to be taken in the case of the strip 16^a.

70 It will appear from the foregoing description that I have provided a novel fastener for use in the application of wall board which considerably reduces labor cost and minimizes the cost of materials. The strips in addition to being easy to handle and fasten into place give the desired even nailing surface for the wall board panels and serve to grip and support the wall board so that warpage and bulging are positively avoided.

75 I am aware that changes in the form and construction of the strips may be made and substituted for those herein shown without sacrificing the more important advantages described. It will, therefore, be understood 80 that the invention is in no way limited to the specific forms illustrated.

85 I claim:

1. In a wall or similar construction, the 90 combination with ordinary spaced wooden studding and wall board arranged to be nailed to the studding, of thin, stiff, metallic strips fastened cross-wise onto the edges of the wooden studding under the wall board, 95 each strip extending in a continuous length 100 across a plurality of studs with at least a portion thereof preferably embedded in the edge of each stud so that the strip projects only slightly therefrom and a substantially 105 flat surface is afforded for the application of the wall board, and all of the strips together 110 serving to back up the wall board between the studding and take the place of separate 115 wooden header pieces otherwise inserted and nailed between the studding.

120 2. In a wall or similar construction, the combination with spaced studding and wall board arranged to be nailed to the studding, of thin, stiff, metallic strips fastened cross-wise to the studding under the wall board, 125 each strip extending in a continuous length across a plurality of the studs so that all of the strips together serve to back up the wall board between the studding and take the place of separate wooden header pieces otherwise inserted between the studding, and each strip having spurs or barbs projecting therefrom arranged to imbed themselves in the wall board so that all of the strips together serve 130

also to hold the wall board against creeping.

3. As a new article of manufacture, a sheet metal header strip arranged to be fastened crosswise to studding to back up wall board nailed thereto, said strip having one or more longitudinal ribs formed in the sheet metal thereof to insure straightness as well as lend sufficient stiffness to resist the tendency for transverse bending under strain, and said strip having two rows of spurs or barbs struck from the sheet metal thereof on opposite sides of a longitudinal median line arranged to imbed themselves in the back of a piece of wall board or in the marginal edge portions of two abutting pieces of wall board.

4. As a new article of manufacture, a sheet metal header strip arranged to be fastened crosswise to studding to back up wall board nailed thereto, said strip having a central 20 longitudinally extending rib crimped in the sheet metal thereof serving to insure straightness of the strip as well as lend sufficient stiffness to resist the tendency for transverse bending under strain, the said rib being 25 adapted to imbed itself readily in the studding in the fastening of the strip thereto, and said strip having two rows of spurs or barbs struck from the sheet metal thereof on opposite sides of said central rib arranged to 30 imbed themselves in the back of a piece of wall board or in the marginal edge portions of two abutting pieces of wall board.

5. As a new article of manufacture, a sheet metal header strip arranged to be fastened crosswise to studding to back up wall board nailed thereto, said strip having a central longitudinally extending rib crimped in the sheet metal thereof serving to insure straightness of the strip as well as lend sufficient stiffness to resist the tendency for transverse bending under strain, the said rib being 40 adapted to imbed itself readily in the studding in the fastening of the strip thereto, and said strip having longitudinally extending flanges on the opposite edges thereof bent inwardly toward one another so as to present rounded edges on the strip, making it easier to handle the same as well as to afford additional stiffness, the said flanges being 45 arranged to be flattened out on the studs and to become slightly imbedded therein in the fastening of the strips to the studding.

6. As a new article of manufacture, a sheet metal header strip arranged to be fastened crosswise to studding to back up wall board nailed thereto, said strip having a central longitudinally extending rib crimped in the sheet metal thereof serving to insure straightness of the strip as well as lend sufficient stiffness 55 to resist the tendency for transverse bending under strain, the said rib being adapted to imbed itself readily in the studding in the fastening of the strip thereto, said strip having two rows of spurs or barbs struck from the sheet metal thereof on opposite sides of 60

said central rib arranged to imbed themselves in the back of a piece of wall board or in the marginal edge portions of two abutting pieces of wall board, and said strip having longitudinally extending flanges on the opposite edges thereof bent inwardly toward one another so as to present rounded edges on the strip, making it easier to handle the same as well as to afford additional stiffness, the said flanges being arranged to be flattened out on the studs and to become slightly imbedded therein in the fastening of the strips to the studding.

In witness of the foregoing I affix my signature.

ALBERT A. McGUIRE.
